CHARLES M. STRATTON AND OSCAR G. STRATTON, OF GREENFIELD,
MASSACHUSETTS.

Letters Patent No. 105,605, dated July 19, 1870.

IMPROVEMENT IN POWER-PRESS.

The Schedule referred to in these Letters Patent and making part of the same

To all whom it may concern:

Be it known that we, CHARLES M. STRATTON and OSCAR G. STRATTON, of Greenfield, in the county of Franklin and State of Massachusetts, have invented certain Improvements in Power-Presses for Punching and Shearing Metals, of which the following is a specification, reference being had to the accompanying drawing.

Our invention relates to presses for punching or shearing metals; and

It consists in a novel construction and arrangement of the parts, whereby the moving plate to which the punch or shearing-blade is attached may be adjusted higher or lower, as to the bed, and also to have a greater or lesser stroke, as may be desired, all as hereinafter explained.

Figure 1 is a longitudinal vertical section of our improved machine on the line $y y$ of fig. 2.

Figure 2, a transverse vertical section on the line $x x$ of fig. 1.

Figures 3, 4, and 5, views of portions shown in detail.

In constructing our press we provide a frame, A, having a bed, B, in the usual manner.

The upper portion of the frame A is bored through, longitudinally, or is cast with an opening or hole extending through it, which is subsequently bored out smooth, and is of sufficient size to receive a large cylindrical sleeve, C, as shown in figs. 1 and 2.

This sleeve C, about midway of its length, is provided with a circumferential groove on its exterior, having a screw-thread formed therein crosswise of the groove, as shown in fig. 2, and through a hole in the frame, at a point corresponding with the groove in the sleeve C, we secure a screw-rod, N, the thread of which corresponds with and engages in the thread in the groove, so that, by turning the rod N, it operates upon and turns the sleeve C in its bearing in the frame A.

This sleeve C is likewise bored through, longitudinally, the hole being located eccentrically in the sleeve, as shown in figs. 1, 2, and 3, and in this eccentric bore is located the driving-shaft D, which extends back of the frame some distance, and having mounted upon it a sliding collar, I, and the driving-wheel G, both of which are loose on the shaft.

At its rear extremity a collar, J, is secured rigidly to the shaft D, and from the inner face of this collar there projects a pin, l, as shown in fig. 1.

To the sliding collar I is attached a pin, o, which extends loosely through a hole in the hub of the wheel G, and the end of which, when the collar I is forced over against the wheel by the lever H, protrudes through the opposite side of the wheel, and

comes in contact with the side of the pin l, thereby locking the wheel fast upon the shaft D, and, of course, causing the shaft to turn with the wheel, the sliding collar and its pin o, in connection with the collar J and its pin l, thus forming a clutch, by which the shaft D may be caused to rotate with the wheel, or to remain stationary, at will.

This driving-shaft D is also bored through, longitudinally, its bore being, in like manner, eccentric, and fitted within its bore is another shaft, E, having, upon its front end, a crank or wrist-pin, a, which carries a box, e, that slides freely in a transverse opening in the face-plate F, in the usual manner.

On the rear end of this inner or crank-shaft E is secured, rigidly, a collar, L, corresponding in size with the collar J on the shaft D, as shown in fig. 1.

The inner collar J has a series of holes bored in a circle in it, as shown more clearly in fig. 5, and corresponding with this circle of holes is one or more holes in the outer collar L, so that, by inserting a pin, n, through a hole in both collars, J and L, as represented in fig. 1, the two shafts, D and E, will be locked together, and thus the wrist-pin a be made to move with the shaft D.

By this method of constructing and arranging the several parts, we are enabled to produce a machine that is exceedingly strong, and in which the bearing-surfaces are of such length or extent that the friction is spread over a large surface, thus causing but very little wear, and rendering the machine more durable and certain to retain its accuracy of movement for a much longer time.

At the same time, and what is of great importance in this class of machines, we provide for adjusting and regulating the length of the stroke with the utmost facility, and also for adjusting the face plate F, which carries the punch or cutting-blade, as the case may be, nearer to or further from the bed B, to suit different thicknesses of metal with the utmost accuracy and dispatch.

By withdrawing the pin n and turning the collar L, and with it the shaft E, to which it is attached, the wrist-pin a will be turned, so as to be nearer to or further from the center of the driving-shaft D, as represented in figs. 3 and 4, the former showing the wrist-pin a at its most eccentric position, in which case it will make a correspondingly long stroke, and fig. 4 representing it very near the center of shaft D, in which case it will make a correspondingly short stroke, it being obvious that it may be adjusted at any intermediate point between these two extremes.

By turning the screw-rod N, which is provided with a hand-wheel for the purpose, the sleeve C will be turned in the frame A, and, as the shaft D is located

eccentrically within the sleeve C, the shaft D, with the crank-shaft E, will be raised or lowered, according as the thick or thin side of the sleeve C is brought to the upper side.

It will be observed that, to make either of these adjustments, the machine need not be taken apart, and that no tool is required, both being readily and easily effected by the hand.

Having thus described our invention,

What we claim is—

1. The combination of the frame A, adjustable eccentric sleeve C, and shaft D, having the adjustable shaft E, with its eccentric wrist-pin located eccentric-

ally therein, and all constructed and arranged to operate substantially as described, for adjusting the plate F to or from the bed B, as set forth.

2. The combination of the driving-shaft D, with the collar J secured thereto, and the crank-shaft E, having the collar L mounted thereon, when arranged eccentrically to each other for adjusting the length of stroke, as set forth.

CHARLES M. STRATTON.
OSCAR G. STRATTON.
